US0D1078461S

(12) **United States Design Patent** (10) **Patent No.:** **US D1,078,461 S**
(45) **Date of Patent:** **** Jun. 10, 2025**

(54) **LOCK PIN REMOVAL TOOL**

(71) Applicant: **Eugene James Partida**, San Dimas, CA (US)

(72) Inventor: **Eugene James Partida**, San Dimas, CA (US)

(**) Term: **15 Years**

(21) Appl. No.: **29/971,218**

(22) Filed: **Nov. 1, 2024**

(51) LOC (15) Cl. **08-05**

(52) U.S. Cl.

USPC **D8/14**; D8/29

(57) **CLAIM**

The ornamental design for the lock pin removal tool, as shown and described.

DESCRIPTION

FIG. 1 is a top front perspective view of a lock pin removal tool showing my new design;

FIG. 2 is a front elevation view thereof, with the rear elevation view being a mirror image thereof;

FIG. 3 is a top elevation view thereof, with the bottom elevation view being a mirror image thereof;

FIG. 4 is a right elevation view thereof, with the left elevation view being a mirror image thereof; and,

FIG. 5 is a section view thereof, taken along line 5-5 of FIG. 4.

The portions of the figures illustrated in broken lines are provided for illustrative purposes only and form no part of the claimed design.

1 Claim, 2 Drawing Sheets
